UNITED STATES PATENT OFFICE.

ALBERT EDWARD STIRCKLER, OF NORTHAMPTON, ENGLAND.

LASTING-MACHINE.

SPECIFICATION forming part of Letters Patent No. 623,848, dated April 25, 1899.

Application filed July 19, 1898. Serial No. 686,331. (No model.)

To all whom it may concern:

Be it known that I, ALBERT EDWARD STIRCKLER, engineer, a citizen of the United States, and a resident of 26 Billing road, 5 Northampton, in the county of Northampton, England, have invented certain new and useful Improvements in Machines for Lasting Boots and Shoes, which invention is fully set forth in the following specification.

10 This invention relates to improvements in certain parts of the lasting-machine for which I have applied for United States Letters Patent on the 24th day of December, 1897, Serial No. 663,364. In the machine described in the 15 specification accompanying the said application the last, with the upper to be lasted thereon, is clamped between toe and heel clamps or heads carrying wiper-plates which wipe the toe and heel ends of the upper over onto the last. 20 The toe clamp or head carries a gripping-jaw, between which and the wiper-plates the upper is held. A rising motion is given to the said clamp, while the last is prevented from rising by a rod carried by the clamp being 25 held in contact with the last, and by the pressure exerted on the said rod the clamp and the gripping-jaw, with the upper held between them, rise and stretch the upper, which is then wiped over the toe of the last by the forward movement of the wiper-plates. 30 Side drafting - nipper wipers are also provided which stretch the upper over the sides of the last, and it is to these parts of the machine that my present invention has special reference; but it also has reference to other parts 35 of the machine, which will be hereinafter described with reference to the accompanying drawings.

Figure 1 is a side elevation of the toe clamp 40 or head, showing one arrangement of wedges for retaining the said head in its elevated position; and Fig. 2 is an end view of the same. Fig. 3 is a side elevation of the toe-head, showing a compound arrangement of wedges for 45 assisting in raising the said head and for retaining it in the elevated position. Fig. 4 is a plan of the longitudinally-sliding portion of the head, showing the position of the wedges; Fig. 5, a detached perspective view of the toe- 50 pad for wiping or smoothing the upper at the extreme toe end of the last and for assisting in holding the said toe end of the upper in its stretched position. Fig. 5^A is a similar view of the pad for pressing against the heel of the

last. Fig. 6 is a plan of the heel clamp or 55 head provided with a divided heel-ring and heel-pad for holding the heel portion of the upper in position on the last. Fig. 7 is a side elevation of one of the outside blocks of a set of three blocks, which carry the drafting- 60 nipper wipers for stretching the upper over the side of the last; Fig. 8, an end view of the said block, and Fig. 9 is a plan of the same. Fig. 8^A is a sectional elevation of part of the center block. Fig. 10 is a side elevation of the 65 mechanism for operating the side drafting-nipper wipers and for restricting the movement of the blocks carrying the said drafting-nipper wipers. Fig. 11 is an end elevation of one of the slides carrying the blocks on which 70 the side drafting-nipper wipers are mounted, and also the mechanism for restricting the movement of the said slide; and Fig. 12 shows in elevation a device for permitting the side drafting-nipper wipers being disengaged from 75 and engaged with the upper while the toe and heel supports are in their operating position.

Referring to Figs. 1 and 2, A represents the rising portion of the toe clamp or head hinged at 1 to a block 2, carried on the upper ends of 80 rods or studs 1^X, surrounded by springs 3, which bear at their lower ends on nuts 3^X, screwed onto the lower ends of the said rods or studs and at their upper ends against the under side of the longitudinally-sliding plate 5, 85 carrying the portion A of the said toe-head, the said springs permitting of the clamp yielding to the desired extent for the lasting operation, the toe-rest determining the height to which the clamp is permitted to rise and also admits 90 of the head rocking in a lateral direction on the stud 4^X. 4 are guides provided on the plate 5, between which guides the block 2 is fitted to slide up and down. So far this mechanism is the same as that described in the application hereinbefore referred to. According to my present invention I provide on the plate 5, so as to slide thereon, a frame B, having wedge-shaped projections B², the said frame being pivoted at a to a lever C, centered at b to the sliding plate 5. When the portion A of the clamp or head is elevated, which may be effected in any suitable manner, the said clamp can be maintained in its elevated positions by moving the lever C in 100 the direction to bring the wedges B² beneath rollers c, carried on the spindle or hinge-pin 1, which connects the block 2 to the portion

A, which hinge-pin is mounted in bearings 2^x on the under side of the said portion A of the clamp, the wedges thus inserted admitting of the last with the upper lasted thereon being released and removed while the clamp remains elevated, and thus prevent any liability to abrade the upper when removing the last from the machine.

- In the modification illustrated by Figs. 3 10 and 4 the wedges B²¹ are made pointed, so as to be capable of entering beneath the roller c' on the extreme forward end of the portion A of the clamp, beneath which rollers the said wedges may be forced by the lever C 15 when the portion A of the clamp is in its normal lower position, and so raise or assist in raising the said clamp. These wedges are employed in the manner described when strong material is being stretched on the last, but 20 are capable of being moved out of action, the said wedges having slots i therein, through which pass studs from the frame B, on which studs the wedges can be slid and be affixed in position by nuts i², screwed onto said studs. 25 When the upper consists of a lighter material, the wedges B²¹ are fixed in their backward position and other wedges B³, carried by the frame B, brought forward to act on rollers f^{xx}, carried by the block 2, to which 30 the clamp A is pivoted. The wedges B²¹ or B³ may be employed alone for raising the toe clamp or head and the elevating device carried on the top plate of the clamp be dispensed with, in which case any suitable gripping device with an adjustable downhold 35 may be provided to grip the upper between the said gripping device and the wiper-plates carried in the said clamp or head. The toe clamp or head is provided with an adjustable 40 pad d, Fig. 5, which is provided with a conical projection d', fitting a corresponding recess in the holder d², screwed onto a screw-threaded rod and pressed forward by a spring, so as to cause the pad d to press upon the 45 upper at the toe end of the last and smooth the said upper at this part and retain it in its stretched position. The said pad is free to turn or rock in the holder d² to accommodate itself to the shape of the toe of the last 50 whether it be a "left" or a "right," and it can be readily removed from the holder and a pad of different shape be fitted in its place.

The heel clamp or head A², as shown in Fig. 6, is provided with a pad e, (shown separately 55 in Fig. 5^a,) similar in construction to the toe-pad d and removable from the holder to admit of pads of different sizes and shapes to suit the size and shape of the lasts being readily fitted to the said holder. This heel-pad projects from the clamp beneath the wiper-plates carried on the said clamp to bear 60 against the upper at the heel end of the last, which pad can be caused to project more or less from the said head by an adjusting-screw e'. Instead of the ordinary band hitherto 65 employed for grasping the upper round the heel of the last I provide plates e² to bear on

the upper at the opposite sides of heel portion of the last, the said plates being pressed against the said upper with a yielding pressure by springs e³, interposed between the plates e² and shoulders e⁵ in passages in the head through which the stems e^{4x} pass, which plates, in conjunction with the pad e, serve to hold the last in proper position for the correct 70 wiping over of the heel portion of the upper by the wiper-plates carried in the said heel clamp or head. The plates e² can be adjusted in position to suit lasts of different sizes and shapes by means of nuts e⁴, screwed onto the 80 stems e^{4x}, carrying the plates e².

The drafting-nipper wipers for stretching the upper at the sides of the last in machines of this kind hitherto in use are pivoted to sliding bars, so that they can be turned in a 85 horizontal plane on the said sliding bars, and the said bars are caused to slide in a direction at right angles to the center line of the last. Consequently the upper, which is engaged in the nippers, is pulled in the said 90 right-angular direction.

According to my present invention, as shown in Figs. 7, 8, and 9, each drafting-nipper F is mounted on a stud f, projecting from the forward end of the sliding bar f', so as to 95 be capable of rocking on the said stud, but it has no movement in a horizontal direction on the said sliding bar f'. The block F', in which the bar f' slides, is hinged at f² to lugs formed on a screwed stem f³, situated in a 100 vertical hole in a block F² beneath the block F' and screwing into a nut f⁴, adapted to turn in a notch or opening f⁵ in the said block F², so that by rotating the nut f⁴ the block F' 105 can be raised more or less from the block F² to permit of the drafting-nipper easily passing over the side of the last. The screwed stem f³ can turn freely in the vertical hole in the block F², so that the block F' can turn in a horizontal plane, which horizontal movement can be restricted by a pin f⁶ in the block F² coming into contact with the ends of a notch f^{xx} in the under side of the block F'. The block F' can also turn in a vertical 110 plane on the hinge f², the said vertical movement being restricted by pins f⁶ in the block F' traversing notches f⁷ in the lugs to which it is hinged, or vice versa. The blocks F², carrying the outside drafting-nipper of each 115 set of drafting-nippers on opposite sides of the last, can be separately adjusted in position in base-plates F³, nearer to or farther from the center block to suit lasts of different lengths, by means of screws f⁸, as shown 120 in Fig. 8^a, working in corresponding screw-threads in the two outside blocks F² of the set of drafting-nippers to adjust the two outside blocks F². The base-plates F³, in which the blocks F² slide, can be adjusted and 125 fixed in position on the frame of the machine, nearer to or farther from the longitudinal center line of the last, as required, to suit rights or lefts, for which purpose slots f^{8x} are 130 provided in the base-plates, through which

125

slots screwed studs f^9 on the frame of the machine pass and on which studs nuts f^{10} are screwed to fix the said base-plates in their adjusted positions.

5 By arranging the blocks F' to turn in a horizontal plane in combination with the adjustability of the blocks F^2 nearer to or farther from each other the slides f' , carrying the drafting-nippers, can be arranged to pull the 10 upper engaged by the said nippers in any desired angular direction with reference to the center line of the last, and the nippers can be engaged with the upper at any point desired, so that the drafting of the upper can be efficiently effected in any desired direction. For 15 instance, the blocks carrying the center nipper and the outside nipper nearest the toe end of the last can be turned to such an angle that the nipper can be engaged at the most 20 advantageous points to stretch the upper toward the toe of the last, while the block F^2 , carrying the nipper on the other side of the center nipper, can be arranged to stretch the upper in the direction toward the heel of the 25 last and so prevent any fullness of leather in the waist of the last. The slides carrying the drafting-nippers are operated by rods and levers 63, 63^X, 63^{XX}, and 64, actuated by a cam or wedge 70 and sliding rods 67, the fulcra of 30 said levers being carried in brackets g on the base-plates F^3 , in which the blocks F^2 on opposite sides of the last slide, as shown in Figs. 10 and 11. Each base-plate is provided 35 on the under side with a recess g^2 , extending to a distance of, say, about two-thirds across the said base, and on a projection g^3 on the frame of the machine on which the base can slide there is a corresponding recess g^4 . In these recesses is placed a helical spring g^5 , 40 which bears at one end against the end of the recess in one of these recesses and at the opposite end against the end of the other recess, so that when the base-plate F^3 is moved outward from the center line of the last the said 45 spring will be compressed between the ends of the two recesses and will return the base-plate to its normal position when the pressure forcing it outward is removed. When the forward movement of the nippers is retarded by tightening the upper over the last, the base-plates F^3 tend to slide outward on the projections g^3 against the power of the springs, which are thereby compressed between the opposing ends of the recesses g^2 g^4 50 unless the outward movement of the base F^3 is prevented. The outward movement of the base-plate on either side or on both sides of the last can be prevented by locking-bolts g^7 , coupled together by a two-armed lever g^8 , centered to a pivot g^{11} , adjustable in the frame 55 of the machine. The bolts g^7 are arranged to slide on studs g^9 in a vertical direction on the frame of the machine, the said studs g^9 passing through slots g^{10} in the bolts. By 60 moving one of these bolts up or down the lever g^8 will rock on the pivot g^{11} , and the other bolt will be moved in the opposite direction, 65

so that when the outward movement of the base-plate on one side of the last is retarded by one of the bolts the base-plate on the other side of the last will be free to move outward against the pressure of the spring g^5 . The bolts g^7 may, however, be moved into an intermediate position, so that the base-plates F^3 on both sides of the last can be free to move outward, or by 70 raising the adjustable pivot g^{11} both base-plates F^3 can be prevented from moving. The base-plate on that side of the last which is most hollow at the waist should be the one prevented from moving outward, so that when 75 the drafting-nipper on the straighter side of the last comes to rest the base-plate will move outward and compress the corresponding spring g^5 , while the base-plate on the opposite side of the last being prevented from 80 moving outward the drafting-nipper on that side of the last will be caused to move farther inward toward the center line of the sole of the last and stretch the upper more closely to the last at the waist. 85

The shaft 71, which carries the cam or wedge 70, when rotated imparts to the side drafting-nippers their movement toward the longitudinal center line of the last. A detent 73 engages the teeth of a ratchet-wheel 72* to prevent the shaft from moving back, and it is necessary to disengage this detent from the ratchet-wheel to permit of the last being removed from the machine. In machines of this kind hitherto in use the detent is retained 90 in gear with the ratchet-wheel by a projection from the lever 88, by which the heel-support is operated, and it is necessary to move the said lever 88 in the direction to lower the heel of the last, and thus place the parts of the 95 machine out of position to release the said detent. According to my invention the said detent can be disengaged from and held out of engagement with the ratchet-wheel 72* without shifting the lever 88. A convenient 100 arrangement for this purpose is to connect to the tail end 75 of the detent 73 a wire or rod h , provided with a loop h' to engage with a hook h^2 on the lever 64 or any other suitable part of the machine to hold the detent out of 105 engagement with and permit of the last being released and removed from the machine and another last of the same size placed in the machine without lowering the heel and toe supports or disarranging other parts of the 110 machine. 115

I claim—

1. In a machine for lasting boots and shoes, the combination of a toe-clamp and springs depressing said clamp, with wedges capable 125 of movement beneath said toe-clamp, and means for moving said wedges.

2. In a machine for lasting boots and shoes, the combination of a toe-clamp with a plurality of wedges beneath said clamp and capable of movement in different transverse vertical planes and means for adjusting said 130 wedges.

3. In a machine of the kind hereinbefore re-

ferred to the combination with the toe-clamp, of a toe-pad projecting from the clamp beneath the wiper-plates carried in the said clamp, a holder for the said pad a conical 5 opening in the said holder, and a conical projection on the pad fitting into the opening in the holder so as to admit of the pad turning in the holder to adjust itself to lasts of different shapes substantially as hereinbefore 10 described.

4. In a machine of the kind hereinbefore referred to the combination with the heel-clamp of a pad, a holder for the pad a conical projection on the pad, a conical recess in the 15 holder to receive the conical projection on the pad carried by the said clamp, a screw for adjusting the pressure of the pad more or less from the said clamp or head, plates for bearing on the sides of the heel of the last, screwed 20 shanks projecting from the plates and fitting loosely in openings in opposite sides of the clamp springs acting on the plates to press them against the sides of the heel of the last and nuts on the screwed shanks of the plates 25 for adjusting the position of the plates to suit lasts of different sizes and shapes substantially as hereinbefore described.

5. In a machine of the kind hereinbefore referred to the combination with the block F² 30 of the block F' pivoted thereto so as to turn in a horizontal plane, a bar slideable in the pivoted block F' and a drafting-nipper pivoted to the slideable bar so as to rock in a vertical plane for stretching the upper over the 35 sides of the last in the direction required substantially as hereinbefore described.

6. In a machine of the kind hereinbefore referred to the combination with the block F² of the block F' pivoted thereto so as to turn 40 in a horizontal plane and a stop to limit the horizontal movement of the said block substantially as hereinbefore described.

7. In a machine of the kind hereinbefore referred to the combination with the block F² of the block F' pivoted thereto so as to turn in a 45 horizontal plane, a screw-thread on the pivot on which the block F' turns, and a nut screwed onto the pivot and adapted to turn in a notch or opening in the block F² so that by turning 50 the nut on the screw-threaded pivot the said pivot together with the block F' can be raised and lowered substantially as hereinbefore described.

8. In a machine of the kind hereinbefore referred to the combination with the block F² of the block F' hinged to a pivot-pin carried by 55 the block F² so as to be free to turn on the said pivot-pin in a vertical plane and a stop to limit the movement of the block F' in a 60 vertical plane substantially as hereinbefore described.

9. In a machine of the kind hereinbefore referred to the combination with the block F² and the block F' pivoted thereto to turn in a 65 horizontal plane and in a vertical plane a base-plate on which the block F² can slide the said plate being adjustable in position on the

frame of the machine toward and from the longitudinal center line of the machine substantially as hereinbefore described. 70

10. In a machine of the kind hereinbefore referred to the combination of the block F' a rod or bar slideable on the said block a nipper fitted to rock on a vertical plane on the said slide, the block F² to which the block F' is 75 pivoted so as to be free to turn on a horizontal plane and also in a vertical plane, a base-plate on which the block F² can slide, slots in the base-plate, studs passing through the slots for fixing the base-plate in position on the 80 frame of the machine substantially as hereinbefore described.

11. In a machine of the kind hereinbefore referred to the combination with blocks F' F² on opposite sides of the machine and base- 85 plates F³ on which the blocks F² are mounted, of recesses in the under sides of the base-plates; corresponding recesses in the frame of the machine; springs in the recesses; projections on the base-plates against which one end 90 of the springs bear projections on the frame of the machine on which the other ends of the springs bear; an arm on each of the base-plates and movable therewith, and to which arms the levers which operate the drafting- 95 nipper wipers are pivoted; bolts on the opposite sides of the machine; a two-armed lever pivoted to the frame of the machine for moving the bolts into position to prevent the movement of the base-plate on one side of the machine or into position to prevent the movement of the base-plates on both sides of the machine or into position to allow the base- 100 plates on both sides of the machine to move substantially as hereinbefore described. 105

12. In a machine of the kind hereinbefore referred to the combination with the mechanism for operating the side wiper-nippers of the ratchet-wheel 72^X and detent 73 and means for disengaging the detent from the ratchet-wheel and retaining it out of engagement therewith without disturbing the position of the supports for the last in the machine substantially as hereinbefore described. 110

13. In a machine of the kind hereinbefore referred to the combination with the mechanism for operating the side drafting-nipper wipers and the ratchet-wheel 72^X and detent 73 for retaining the parts in position to which they are moved, of a rod or wire connected at 115 one end to the detent, a loop at the other end of the rod or wire a hook with which the loop can be engaged to retain the detent out of engagement with the ratchet-wheel substantially as and for the purpose hereinbefore described. 120

In testimony whereof I have signed this specification in the presence of two subscribing witnesses.

ALBERT EDWARD STIRCKLER.
